UNITED STATES PATENT OFFICE

2,566,621

BRUSH SPINDLE

George L. N. Meyer, Milwaukee, Wis., assignor
to Geo. J. Meyer Manufacturing Company,
Cudahy, Wis., a corporation of Wisconsin

Application April 9, 1949, Serial No. 86,432

4 Claims. (Cl. 15—128)

1

This invention relates to a brush spindle adapted for use on bottle washing machines.

It is an object of the present invention to provide a brush spindle which will accommodate itself to misaligned bottles.

It is another object of the present invention to provide a readily replaceable, flexible, hollow shaft to support a brush.

Another object is to reduce the cost of replacing brushes in a bottle washing machine.

A further object is to provide a brush spindle which will facilitate the replacement of brushes.

A further object is to provide an improved relatively flexible brush spindle.

A still further object is to provide a brush spindle for a bottle washing machine which will eliminate inside scratches in bottles.

Still further objects will become apparent upon considering the following specification, which when considered with the accompanying drawings illustrate a preferred form of the invention.

In the drawings:

Fig. 1 is a side elevational view of a brush spindle embodying the present invention;

Fig. 2 is an enlarged cross-sectional view taken on the line 2—2 of Fig. 1; and

Fig. 3 is an enlarged cross-sectional view taken on the line 3—3 of Fig. 1.

Referring to the drawings, and particularly to Fig. 1, the brush spindle comprises a fitting 10 adapted to screw onto a spindle head, a flexible hollow shaft 12 and a brush head generally designated 15 carrying a brush 16.

The fitting 10, (Fig. 3) has a square base 17 to facilitate screwing the fitting onto a rotatable spindle head (not shown). A cylindrical extension 18 is formed on the upper end of the square base 17. The interior of the fitting 10 is provided with a pair of concentric bores 19 and 20.

The lower bore 19, which extends into the square base of the fitting is provided with screw threads adapted to engage corresponding threads on the spindle head.

The hollow flexible shaft 12 is composed of a tightly wound coil spring of sufficient transverse stiffness to retain the shaft against flexing during rotation about its axis and to transmit water from the spindle head through the brush 16.

The bore 20 is threaded with a groove of slightly greater pitch than the pitch of the spring shaft 12 so that as the lower end of the spring 12 is screwed into the bore 20 the coils of the spring will be expanded to form an automatic locking device. The end of the spring may strike an abutment 20' to limit the inward movement of

2

If desired the piece 17 may be formed integral with the spindle head, and form a part thereof. In this event the bore 20 with the groove therein would be formed directly in the spindle head.

5 The upper end of the spring 12 is turned into a spiral groove or thread in a nipple 21 of the brush head 15. The groove or thread in the nipple 21 may be the same pitch as the spring tube 12 and the direction of rotation of the spring tube 12 about the vertical axis is such as to tend to tighten the nipple 21 on the spring tube 12 as the spring tube rotates. The end of the spring tube 12 abuts against a shoulder 21' in the nipple 21 to limit the movement of the spring into the nipple.

A pin 22 supports the brush 16. The brush 16 is fully described and claimed in applicant's co-pending application for U. S. Patent for Inside Bottle Brush, Serial No. 591,884, filed May 4, 1945.

20

Operation

In operation the fitting 10 is screwed on the rotatable spindle head in a bottle washing machine (spindle head not shown). When the bottle is in alignment with the brush spindle the forward movement of the bottle is stopped and the brush spindle raised into the bottle.

25 As the brush spindle raises it is rotated by the spindle head in a direction tending to screw the spring 12 further into the nipple 21. Since the spring 12 is held in the fitting 10 by a locking action, there is no tendency for the spring to become disengaged from either nipple 21 or the fitting 10.

30 As the brush rotates in the bottle to be cleaned, water is supplied from the rotatable spindle head, through the spring tube 12, through the nipple 21 to the interior of the bottle to wash it.

The provision of the spring tube 12 permits 35 ready entry of the brush to the bottle when the bottle is misaligned in the carrier and thus prevents interior bottle scratching.

40 It will be realized that the hereinbefore described form of the invention is to be taken merely as a preferred embodiment thereof and that various changes in size, shape and arrangement of parts may be resorted to without departing from the spirit of the invention or the scope of the subjoined claims.

45 50 That which is claimed as new and is desired to be secured by United States Letters Patent is:

1. In a device of the character described, a brush spindle adapted to attach to a rotatable spindle head, said brush spindle comprising, a nipple, a brush mounted in one end of said nipple, a flexible tubing comprising a closely wound

spring adapted to transmit rotation and to conduct fluid from the spindle head to the brush, and screw threads in the nipple engaging the coils of the spring to retain the same in the nipple.

2. A brush spindle for use on a rotary spindle head comprising, a fitting adapted to be attached to the rotary spindle head, a nipple, an inside bottle brush connected with said nipple and a closely wound spring forming a liquid transmitting medium between the nipple and the fitting and screw-threaded into both the nipple and the fitting.

3. A brush spindle for use on a rotary spindle head comprising, a fitting adapted to attach to the rotary spindle head, a nipple adapted to carry an inside bottle brush, a closely wound spring forming a liquid transmitting medium screw-threaded into both the nipple and the fitting and adapted to transmit liquid therebetween, and means to lock the spring in said fitting.

4. In a brush spindle for use on a rotary spindle head, a fitting adapted to attach to the ro-

tary spindle head, said fitting having a vertical aperture in the upper end thereof provided with a helical groove, and a closely wound helical spring having a smaller pitch than said groove, said spring screwing into said groove with the difference in pitch forming a locking member to prevent accidental unscrewing.
